UNITED STATES PATENT OFFICE.

HOWARD R. SARGENT, OF SCHENECTADY, NEW YORK, ASSIGNOR TO GENERAL ELECTRIC COMPANY, A CORPORATION OF NEW YORK.

LAMP-TRIMMING.

No. 853,899.

Specification of Letters Patent.

Patented May 14, 1907.

Application filed February 8, 1904. Serial No. 192,277.

To all whom it may concern:

Be it known that I, HOWARD R. SARGENT, a citizen of the United States, residing at Schenectady, county of Schenectady, State 5 of New York, have invented certain new and useful Improvements in Lamp-Trimmings, of which the following is a specification.

My present invention relates to trimmings or fittings particularly adapted for use in 10 connection with electric lamps though not entirely limited to such use.

The various novel features of construction and arrangement which characterize my invention are pointed out with particularity in 15 the claims annexed to and forming a part of this specification.

For a better understanding of my invention, however, reference may be had to the accompanying drawings and description in 20 which I have illustrated and described one form in which it may be embodied.

Figure 1 is an elevation with parts in section and parts broken away showing an electric lamp equipped with my invention, and 25 Fig. 2 is a sectional elevation of the fitting.

Referring to the drawings, 1 represents a socket such as that ordinarily employed to receive incandescent electric lamps. The socket is formed with an annular bead 2 located slightly above the lower end of the 30 shell of the socket. A lamp 3 is secured in the socket 1 in any suitable manner as by a threaded connection. The globe 4 of the lamp is shown in the drawings as approximately spherical. The lower portion of the globe may be frosted as shown. A portion of the upper surface of the globe, preferably unfrosted, is covered by the zonular portion of a reflector member 5 which may be formed 35 out of sheet metal or other suitable opaque or translucent material.

An expansible collar or fitting 6 extends between the bead 2 and the reflector member 5. In the form of my invention shown 45 in the drawings the collar 6 comprises annular shell members 7 and 8, which may be formed out of spun metal, and a helical spring 9.

The shell member 8 comprises a portion 10 so shaped that each section cut by a plane passing through the axis of the member is 50 outwardly in the form of an outwardly concave arc. The portion 11 of the member 8 immediately above the portion 10 is cylindrical. An outwardly extending flange 12

is formed at the upper end of the portion 11. The flange portion 12 terminates in an upwardly extending cylindrical portion 13.

The member 7 is formed with a cylindrical portion 14 which surrounds the cylindrical 60 portion 13 of the member 7. The extreme lower portion of the member 14 is in the form of an inwardly turned flange portion 15, the inner periphery of which may closely embrace the cylindrical portion 11 of the member 8. The upper portion 16 of the member 7 is curved so that each section cut by a plane passing through the axis of the member is in the form of an ogee curve the lower part of the portion 16 being practically radial. The opening 17 formed at its upper end is just large enough to receive the lower end of the socket 1.

The helical spring 9 extends between the lower radial part of the curved portion 16 of 75 the member 7 and the radial portion 12 of the member 8 and tends to separate the portions 7 and 8 to the extent shown in Fig. 2.

The various parts are so proportioned and arranged that when the lamp 3 is secured in 80 the socket 1 the members 7 and 8 will be telescoped together somewhat between the bead 2 of the socket 1 and the reflector member 5. Under these circumstances the spring 9 serves to firmly secure the parts together with the 85 reflector 5 in proper position with respect to the globe 4.

The use of the elastic collar 6 obviates the necessity of making nice calculations in proportioning the parts. The collar also serves 90 to conceal and protect the upper portion of the lamp and the lower end of the socket.

It will, of course, be understood that the particular shapes given to the various parts of the collar are not essential features of my invention. I contemplate that various deviations can be made in the form and arrangement of the parts employed in the construction of the collar without departing from the spirit of my invention. 100

What I claim as new and desire to secure by Letters Patent of the United States, is:

1. In combination, a socket, a lamp secured in said socket, a reflector resting against the surface of the lamp, and a longitudinally 105 extensible collar extending between said reflector and said socket.

2. In combination, a socket formed with a bead located adjacent its lower end, a lamp secured in said socket, an annular or zone 110

shaped reflector resting against the globe of said lamp, and an expansible collar one end of which engages the bead on said socket and the other end of which engages said reflector 5 to force it against said lamp.

3. In combination; a socket, a lamp secured therein, a reflector resting against the globe of said lamp, and an expansible collar extending between said socket and said reflector comprising two annular members capable of limited relative movement and a spring tending to separate said members.

4. In combination, a socket, a lamp secured in said socket, a reflector for said lamp resting against a portion of its surface, and a collar formed of telescoping sections extending between said reflector and said socket.

5. In combination, an electric lamp globe or bulb, a zonular reflector through the opening in which the neck of said bulb is passed, and resilient means for pressing said reflector against said globe.

6. In combination, a socket, an electric lamp secured in said socket, a reflector resting against the globe of said lamp, and resilient means extending between said socket and said reflector to hold the latter against the said globe.

7. In combination, a lamp socket, a lamp bulb the neck of which is secured in said socket, a reflector having an opening through which the neck of the lamp bulb passes, and a resilient collar one end of which engages the lamp socket and the other end of which engages the reflector. 30

8. In combination, an electric lamp globe or bulb, a reflector substantially circular in outline formed with a centrally located aperture through which the neck of the bulb or globe is passed, and resilient means for pressing the reflector against the lamp globe. 35

9. In combination, a lamp socket, a lamp bulb the neck of which is secured in said socket, a reflector substantially circular in outline and formed with a centrally located aperture through which the neck of the bulb is passed, and an extensible collar extending between said socket and said reflector to hold 40 said reflector against the lamp bulb. 45

In witness whereof I have hereunto set my hand this 4th day of February, 1904

HOWARD R. SARGENT.
